US00D605652S

(12) **United States Design Patent**
Plaisted et al.

(10) **Patent No.:** **US D605,652 S**
(b4) **Date of Patent:** **** Dec. 8, 2009**

(54) **GRAPHICAL USER INTERFACE FOR COMPUTER**

(75) Inventors: **Joshua Reed Plaisted**, Oakland, CA (US); **Arthur Rene Leblanc, III**, Kennebunk, ME (US); **Gordon Michael Handelsman**, Thousand Oaks, CA (US); **Clive Veroni**, Ontario (CA); **Glenda Rissman**, Ontario (CA); **Darrell John Corriveau**, Ontario (CA); **Gary Ing**, Ontario (CA); **Peter Kirkpatrick**, Ontario (CA)

(73) Assignee: **PVT Solar, Inc.**, Berkeley, CA (US)

(**) Term: **14 Years**

(21) Appl. No.: **29/328,160**

(22) Filed: **Nov. 19, 2008**

(51) **LOC (9) Cl.** 32-00

(52) **U.S. Cl.** **D14/485**

(58) **Field of Classification Search** D14/485-495; 705/28; 715/700, 703, 709, 712, 716, 719, 715/720, 721, 727, 728, 752, 753, 757, 768, 715/771, 772, 777, 782, 808, 809, 810, 812, 715/819, 920, 821, 825, 833, 834, 835, 836, 715/837, 838, 839, 840, 841, 842, 843, 846, 715/848, 849, 850, 851, 852, 856, 861, 864, 715/961, 962, 963, 970, 977

(57) **CLAIM**

The ornamental design for graphical user interface for computer, as shown and described.

DESCRIPTION

The FIGURE is a front view of the graphical user interface for computer according to the present invention.

The text, graphics and portion of a computer screen shown in broken lines form no part of the claimed design.

1 Claim, 1 Drawing Sheet

Good evening Robert, Jun 18, 2008 8:30 pm Logout Energy Production | Weather | Environmentals | Temperature Profiles | Settings

TEMPERATURES | OUTSIDE 72°F | HOME 72°F | WATER 72°F

ENERGY PRODUCTION AT 8:30 PM

2.5 kW	HEATING
2.5 kW	ELECTRICITY

ENERGY PRODUCTION MONDAY, Jun 16, 2008

TOTAL 25kWh	ELECTRICITY 25kWh	HEATING 2.5kWh	COOLING 0.5kWh
